CLAMP FOR THE FLANGES OF MICROWAVE PLUMBING

Alex Reithoffer, 7106 Tunney Ave., Reseda, Calif.

Filed Dec. 10, 1962, Ser. No. 72,780

Term of patent 14 years

(Cl. D54—13)

FIG. 1 is a perspective view of a clamp for the flanges of microwave plumbing, showing my new design.

FIG. 2 is a front elevational view thereof.

FIG. 3 is a rear elevational view.

FIG. 4 is a side elevational view as seen from the left side of FIG. 3.

FIG. 5 is a longitudinal sectional view as taken on the line 5—5 of FIG. 3.

This application is a continuation-in-part of my pending application, Serial No. D-69,629, filed April 9, 1962, and now abandoned.

I claim:

The ornamental design for a clamp for the flanges of microwave plumbing, substantially as shown and described.
